DESIGN FOR A GUN SIGHT

Watrous C. Redfield, Denver, Colo.

Application October 27, 1934, Serial No. 53,792

Term of patent 7 years

To all whom it may concern:

Be it known that I, Watrous C. Redfield, a citizen of the United States of America, residing at Denver, in the county of Denver and State of Colorado, have invented a new, original, and ornamental Design for a Gun Sight, of which the following is a specification, reference being had to the accompanying drawing, forming part hereof.

Fig. 1 is a perspective view of a gun sight, showing my new design.

Fig. 2 is a rear elevation thereof.

Fig. 3 is a side elevation thereof.

I claim:

The ornamental design for a gun sight as shown.

WATROUS C. REDFIELD.
